UNITED STATES PATENT OFFICE.

THOMAS S. AINGE, OF DETROIT, MICHIGAN.

* CHEMICAL-CLOSET.

1,176,122.

Specification of Letters Patent. Patented Mar. 21, 1916.

Application filed May 11, 1914. Serial No. 837,929.

To all whom it may concern:

Be it known that I, THOMAS S. AINGE, a citizen of the United States of America, residing at Detroit, in the county of Wayne 5 and State of Michigan, have invented certain new and useful Improvements in Chemical-Closets, of which the following is a specification, reference being had thereto in the accompanying drawings.

10 The invention relates to closets, and more particularly to that type provided with a removable receptacle in which a disinfectant and decodorant chemical compound is placed when the closet is in use.

15 It is the object of the invention to obtain a simple and inexpensive construction to manufacture and one which has various features of advantage as hereinafter set forth.

20 In the drawings, Figure 1 is a plan view of the closet; Fig. 2 is a vertical central section therethrough; and Fig. 3 is a section through the vent connection, showing the seat in raised position.

25 A is a suitable base, B is a post or standard rising from said base and having secured at its upper end a hinged seat C, D is a removable vessel which is adapted to be placed upon the base A when the seat is raised and 30 which forms a sealing joint with said seat when lowered.

To provide ventilation for the receptacle D, a vent pipe E is arranged preferably in alinement with the standard B, its upper 35 end being connected with a chimney or other escape flue. The lower end of this tube is connected with a lateral conduit F which communicates with a port formed in the seat C and opening into the receptacle

40 D. To permit of hinging the seat, the lateral conduit F is formed in two sections, F' F², the former being permanently mounted upon the post B and the latter upon the seat C. These two sections are 45 preferably provided with hinge lugs G,

which are pivotally connected together as shown in Fig. 3, so that when the seat is lifted the sections F' F² will separate, while in the lowered position these sections abut and form a continuous conduit. 50

With the construction as described, in use the receptacle D being removable can be easily cleansed, and as there is no outer casing to become foul the whole device may be kept in a sanitary condition. The seat 55 when raised permits of easily removing or replacing the receptacle, and when lowered forms the sealing joint with the upper edge of said receptacle, while the ventilating flues F E form an air connection therewith. 60 The whole construction is one which can be cheaply manufactured and easily installed.

What I claim as my invention is,—

1. In a closet, the combination with a 65 base, of a post rising from said base, a vent pipe arranged in alinement with said post, a removable receptacle seated upon said base, a seat for the upper end of said receptacle, and a hinge connection between 70 said seat and post forming a vent passage for connecting said receptacle with said vent pipe.

2. In a closet, the combination with a base, a vent pipe, a removable receptacle 75 seated on said base, a seat having a stationary part fixed in relation to said base and a movable part having a vent opening, and a hinged conduit having a stationary part fixed in relation to said base and in 80 open communication with said vent and a movable part secured to the movable part of said seat and overlying and communicating with the vent opening therein.

In testimony whereof I affix my signature in presence of two witnesses.

THOMAS S. AINGE.
